UNITED STATES PATENT OFFICE.

LEWIS T. HOUGHTON, OF WORCESTER, MASSACHUSETTS.

TOP-ROLL-SADDLE MECHANISM.

1,218,659.

Specification of Letters Patent. Patented Mar. 13, 1917.

Application filed October 20, 1911. Serial No. 655,685.

To all whom it may concern:

Be it known that I, LEWIS T. HOUGHTON, a citizen of the United States, residing at Worcester, county of Worcester, State of Massachusetts, have invented an Improvement in Top-Roll-Saddle Mechanisms, of which the following description, in connection with the accompanying drawing, is a specification, like characters on the drawing representing like parts.

This invention relates to top roll saddle mechanism and particularly to the connection between the stirrup and the weighted lever, the object of the invention being to provide a novel construction by which the point of connection between the stirrup and the weighted lever can be readily adjusted thereby to vary the relative lengths of the lever arms for the purpose of throwing a greater or less weight on the top rolls.

In top roll mechanism it is customary to provide a weighted lever which is fulcrumed at one end on a lever screw or fulcrum member and which is hung intermediate of its ends on the stirrup through which the weight is applied to the top roll saddle. In carrying out my invention I provide a stirrup-positioning member which is movably mounted on the weighted lever and which serves to position the stirrup relative to the lever, the adjustability of the positioning member on the stirrup providing means for adjusting the relative lengths of the lever arms of the lever. In the preferred embodiment of my invention this stirrup-positioning member has such a construction that the position thereof may be shifted thereby to vary the relative lengths of the lever arms without taking the weight off from the lever or without disconnecting the stirrup either from the lever or from the top roll saddle and without affecting appreciably the position of the weighted lever.

Referring to the drawings wherein I have shown a selected embodiment of my invention which is sufficient to disclose the principle thereof, Figure 1 is a view showing in side elevation a top roll saddle mechanism embodying the invention;

Fig. 2 is a section through the weighted lever on the line $x-x$, Fig. 1;

Fig. 3 is a section on the line $y-y$, Fig. 1;

Fig. 4 is a perspective view of the stirrup-positioning member;

Fig. 5 is a perspective view of the portion

of the weighted lever before the positioning member is applied thereto;

Fig. 6 is a section on the line $a-a$, Fig. 2.

1 indicates the usual roller beam, 2 a stand or support rising therefrom, 3, 4 and 5 designate top rolls, and 6, 7 and 8 the bottom rolls which are journaled in the stand 2 in usual manner. The top roll saddle may have any suitable or usual construction as it forms no part of the present invention. Said saddle is herein shown as comprising the under member 9 which rests on the center and rear top rolls and the upper member 10 which rests on the front top rolls and on the under member.

The weight is applied to the top rolls through a stirrup 11 which is hung from a weight-transmitting member 12 that rests on the upper member 10 and is herein shown as connected at one end to a clip 13 that is secured to the cap rail 14. This particular form of top roll saddle construction, however, is not essential to the invention as the improvements to be hereinafter described might be used in connection with any ordinary top roll saddle mechanism.

15 designates a weighted lever which is fulcrumed at one end to a lever screw or fulcrum member 16 carried by the roller beam 1 and from the other end of which is supported a weight 17 by means of a link 18 in usual manner. The weighted lever 15 is hung on the lower end of the stirrup 11 so that the weight 17 is transmitted through the lever and stirrup to the top roll saddle as usual in devices of this class. In the present invention the connection between the stirrup and the lever is an adjustable one which permits the point of engagement between the stirrup and lever to be adjusted toward or from the fulcrum member 16 and a stirrup-positioning member is employed for holding the stirrup in this adjusted position. As shown herein the lever 15 is provided with the slot 19 which extends at right angles to the stirrup and the stirrup 11 is formed with a laterally-projecting finger 20 which is adapted to extend through the slot. Said finger is preferably curved at its upper edge, as at 21, and is provided at its lower edge with a notch 22 which straddles or embraces the lower part 23 of the lever.

The advantage of making the slot 19 at right angles to the stirrup is that the ad-

justment of the finger 20 in the slot does not appreciably change the angle of the weighted lever.

For positioning the stirrup in the notch 19 I employ a stirrup-positioning member which is adjustable longitudinally of the lever and in a direction at right angles to the stirrup. The stirrup-positioning member herein shown is indicated at 24 and is provided with the two side pieces 25 which embrace the weighted lever and overlie the sides thereof, said side pieces each being shown as having an opening 26 therein through which the finger 20 of the stirrup 15 extends. One of the side pieces is shown as having a finger 27 extending laterally from its lower edge and occupying a notch 28 formed in the under side of the lever, said finger and notch serving to limit the sliding movement of the positioning member on the lever. Suitable means are employed for adjusting the stirrup-positioning member on the lever and for holding it in adjusted position, and while my invention contemplates the employment of any suitable means for this purpose, I prefer to provide a construction wherein the stirrup-positioning member can be adjusted on the weighted lever without removing the weight 17 from said lever and without disconnecting the stirrup from the top roll saddle. This end can be accomplished by providing an adjusting screw which co-operates with the stirrup-positioning member and lever to control the position of said member.

In the embodiment herein shown the stirrup-positioning member is provided with an upturned ear 29 provided with an aperture through which extends an adjusting screw 30 that has screw-threaded engagement with a nut 31 carried by and rigid with the lever 15. I have herein shown the stirrup-positioning member as provided with a second apertured ear 32 through which the adjusting screw also passes, said second ear serving to hold the adjusting screw in proper position. The adjusting screw is swiveled to the ear 29 but is held from longitudinal movement relative thereto. This may be accomplished in a variety of ways and in the construction shown the ear 29 is held between the head of the screw and a collar 33 formed on or applied to the adjusting screw. The nut 31 may either be formed integral with the lever 15 or may be a separate part secured thereto. One convenient way of making this device is that shown in the drawings wherein the upper edge of the lever 15 is made with a notch 35 to receive the nut 31, and the latter is formed with the two legs 34 which overlie the sides of the lever 15. The lever is preferably provided with an aperture 36 and the lower ends of the legs 34 may be bent or forced into this aperture by the

action of a hammer or die thereby firmly locking the nut in place.

The stirrup 11 is preferably cut away at one side, as shown at 39, so that the head of the adjusting screw is always accessible. 70

With this construction it will be readily seen that the adjusting screw can be turned by means of a screw-driver thereby to shift the position of the stirrup-positioning member on the lever and to vary the relative 75 lengths of the lever arms of said lever without removing the weight from the lever or disturbing in any way the stirrup or the top roll saddle. Furthermore, because of the screw-threaded engagement between the adjusting screw and its nut a very fine and accurate adjustment of the stirrup-positioning member can be secured. Moreover, the screw thread acts as a means for locking the stirrup-positioning member in its ad- 80 justed position.

In manufacturing my device I prefer to carry the slot 19 as close to the notch 42 in the lever 15 which receives the fulcrum member 16, as possible, and also to form 90 said slot so that its upper edge at the lower end 43 thereof and the bottom of the notch 42 are in substantially the same horizontal line. The advantage of this construction is that when the stirrup is adjusted clear to the 95 lower end of the slot the weight 17 will be applied in the most advantageous manner and without danger that during any movement of the lever the point where the stirrup engages the lever will swing over or 100 below the point of engagement between the lever and the fulcrum member 16. This makes it possible to place the stirrup clear at the lower end of the slot 19 and very 105 close to the fulcrum member 16 and when the stirrup is in this position a very light weight 17 is sufficient to apply the requisite weight to the top roll saddle.

From the above it will be seen that some 110 of the advantages of my present construction are that the stirrup can be readily adjusted so as to apply more or less weight on the top roll according to the requirements of use and such adjustment can be readily effected while the spinning frame is in use and without the necessity of removing the weight from the lever or disconnecting the stirrup from the saddle or making any change whatever. Another advantage results from the right angular relation between the slot 19 and the stirrup, for by 115 means of this construction the adjustment of the stirrup in the slot can be effected, without appreciably changing the angle of the lever. Furthermore, the construction makes it possible to secure all the desired weight on the top roll saddle by using a comparatively light weight on the lever.

I have herein shown the head 50 of the 120 adjusting screw 30 as inclosed in a sleeve 125

which is loosely sustained on said screw. This sleeve acts both to protect the screw from being accidentally turned by any object striking against the screw head, and also to guide the screw driver and hold it in the slot of the screw head when the screw is being adjusted.

While I have illustrated herein one embodiment of my invention, yet since I believe I am the first to use a stirrup-positioning member for holding the stirrup in its adjusted position relative to the lever, I desire to claim this feature broadly and to state that the invention is not limited to the construction shown.

Having fully described my invention, what I claim as new and desire to secure by Letters Patent is:

1. In a top roll saddle mechanism, the combination with a top roll saddle, of a stirrup for applying weight thereto, a fulcrum member, a weighted lever engaging said fulcrum member and hung from said stirrup, and means accessible from the fulcrum end of the lever for adjusting the point of engagement between the stirrup and lever in a direction at right angles to the stirrup thereby to vary the relative lengths of the lever arm of said lever.

2. In a top roll saddle mechanism, the combination with a top roll saddle, of a stirrup for applying weight thereto, a weighted lever hung from said stirrup, a stirrup positioning member adjustable on the lever in a direction at right angles to the stirrup and operating to control the position of the stirrup relative to said lever, and means for adjusting said member on the lever.

3. In a top roll saddle mechanism, the combination with a top roll saddle, of a stirrup for applying weight thereto, a weighted lever hung from the stirrup, a stirrup positioning member slidably mounted on the lever and engaging the stirrup, and an adjusting screw to effect adjustment of and control the position of said member.

4. In top roll saddle mechanism, the combination with a top roll saddle, of a stirrup for applying weight thereto, a weighted lever hung from the stirrup, a stirrup positioning member slidably mounted on the lever and engaging the stirrup, and an adjusting screw having swivel connection with said member and screw-threaded connection with the lever.

5. In a top roll saddle mechanism, the combination with a top roll saddle, of a stirrup for applying weight thereto, a weighted lever hung from the stirrup, a stirrup positioning member slidably mounted on the lever and engaging the stirrup, an adjusting screw carried by said member, and a nut associated with the lever and with which said screw has screw threaded engagement.

6. In a top roll saddle mechanism the com-

bination with a top roll saddle, of a stirrup for applying weight thereto, and provided with a laterally extending finger, a weighted lever having a slot to receive said finger, and a stirrup positioning member engaging 70 said finger.

7. In a top roll saddle mechanism the combination with a top roll saddle, of a stirrup for applying weight thereto, and provided with a laterally extending finger, a 75 weighted lever having a slot to receive said finger, and a stirrup positioning member adjustably mounted on the lever, and engaging said finger.

8. In a top roll saddle mechanism the combination with a top roll saddle, of a stirrup for applying weight thereto, and provided with a laterally extending finger, a weighted lever having a slot to receive said finger, and a stirrup positioning member 85 slidably mounted on the lever, and an adjusting screw to effect adjustment of and control the position of said member.

9. In a top roll saddle mechanism the combination with a top roll saddle, of a stirrup for applying weight thereto, said stirrup having a laterally extending finger, a weighted lever supported by said finger, and a stirrup positioning member straddling the lever and slidably thereon, said member having an aperture to receive the finger.

10. In a top roll saddle mechanism the combination with a top roll saddle, of a stirrup for applying weight thereto, said stirrup having a laterally extending finger, a 100 weighted lever supported by said finger, and a stirrup positioning member straddling the lever and slidably thereon, said member having an aperture to receive the finger, and means to adjust said member on the 105 lever and hold it in adjusted position.

11. In a top roll saddle mechanism the combination with a top roll saddle, of a stirrup for applying weight thereto, and provided with a laterally extending finger, of 110 a weighted lever having a slot to receive said finger, a stirrup positioning member straddling the lever, and having an aperture to receive said finger and an adjusting screw for controlling the position of said member 115 on the lever.

12. In a top roll saddle mechanism the combination with a top roll saddle, of a stirrup for applying weight thereto and provided with a laterally extending finger, a 120 weighted lever having a slot to receive said finger, a stirrup positioning member straddling the lever and provided with an aperture to receive said finger, said member having an ear extending upwardly therefrom, 125 an adjusting screw sustained by said ear, and a nut rigid with the lever and engaging said screw.

13. In a top roll saddle mechanism the combination with a top roll saddle, of a stir- 130

5 rup for applying weight thereto, a weight-
ed lever hung from said stirrup and pro-
vided on its lower edge with oppositely dis-
posed shoulders, a stirrup positioning mem-
ber straddling the lever and having a stop
finger playing between said shoulders, and
means to adjust said member on the lever.

10 14. In a top roll saddle mechanism the
combination with a top roll saddle, of a stir-
rup for applying weight thereto and pro-
vided with a laterally extending finger, a
weighted lever provided with a slot to re-
ceive said finger, and having a notch to re-
ceive a fulcrum member, a fulcrum member
15 occupying said notch, the upper edge of the
slot at the lower end thereof and the bottom
of said notch being in substantially the same
horizontal line, and a stirrup positioning
member engaging said finger.

20 15. In a top roll saddle mechanism the
combination with a stirrup for applying
weight to a top roll saddle, and provided
with a laterally extending finger, of a
weighted lever having a slot to receive said
25 finger, a stirrup positioning member strad-
dling the lever and engaging said finger,
said member having an ear extending up-
wardly therefrom, a nut rigid with said
lever and situated above its upper edge, and
30 an adjusting screw carried by said ear and
having screw threaded engagement with
said nut.

35 16. In a top roll saddle mechanism the
combination with a stirrup for applying
weight to a top roll saddle, and provided
with a laterally extending finger, of a
weighted lever having a slot to receive said
40 finger, a stirrup positioning member strad-
dling the lever and engaging said finger,
said member having an ear extending up-
wardly therefrom, a nut rigid with said le-
ver and situated above its upper edge, and
45 an adjusting screw carried by said ear and
having screw threaded engagement with
said nut, and a guard sleeve loosely mount-
ed on the screw and inclosing the head
thereof.

50 17. In a top roll saddle mechanism the
combination with a stirrup for applying
weight to a top roll saddle, and provided
with a laterally extending finger, of a
weighted lever having a slot to receive said
55 finger, a stirrup positioning member strad-
dling the lever and engaging said finger,
said member having an ear extending up-
wardly therefrom, a nut rigid with said le-
ver and situated above its upper edge, and
60 an adjusting screw carried by said ear and
having screw threaded engagement with
said nut, said stirrup being cut away to
leave the end of the screw accessible, where-
by said screw may be adjusted without dis-
turb any of the parts.

65 18. In a top roll saddle mechanism the
combination with a stirrup for applying

70 weight to a top roll saddle, said stirrup hav-
ing a laterally extending finger, of a weight-
ed lever having a slot to receive said finger,
a stirrup positioning member adjustably
mounted on the lever and engaging said fin-
ger, a nut carried by the lever, said nut hav-
ing two legs which straddle the upper edge
75 of the lever, and an adjusting screw carried
by the stirrup positioning member and hav-
ing screw-threaded engagement with said
nut.

80 19. In a top roll saddle mechanism the
combination with a stirrup for applying
weight to a top roll saddle, and provided
with a laterally extending finger, of a
weighted lever having a slot to receive said
85 finger and provided with an aperture, a
stirrup positioning member adjustable on
said lever and engaging said finger, a nut
provided with a pair of legs which straddle
the upper edge of said lever, and the lower
ends of which are bent into said aperture,
and an adjusting screw carried by the stir-
90 rup positioning member and having screw-
threaded engagement with said nut.

95 20. In a top roll saddle mechanism, the
combination with a top roll saddle, of a
stirrup for applying weight thereto, a ful-
crum member, a weighted lever engaging
the fulcrum member and supported by said
100 stirrup, and a connection between said stir-
rup and said lever which permits the point
at which the lever is supported from the
stirrup to be adjusted toward and from the
fulcrum member in a direction at right an-
gles to the stirrup.

105 21. In a top roll saddle mechanism, the
combination with a top roll saddle, of a
stirrup for applying weight thereto, a
weighted lever hung from said stirrup, and
110 a stirrup-positioning member straddling the
lever, slideable thereon and having operative
engagement with said stirrup.

115 22. In a top roll saddle mechanism, the
combination with a top roll saddle, of a stir-
rup for applying weight thereto, a weighted
120 lever hung from said stirrup, a stirrup-po-
sitioning member straddling the lever, slide-
able thereon and having operative engage-
ment with said stirrup, and means to adjust
125 said member on the lever and hold it in ad-
justed position.

130 23. In a top roll saddle mechanism, the
combination with a top roll saddle, of a stir-
rup for applying weight thereto, a weight-
ed lever hung from said stirrup, a stirrup-
positioning member straddling the lever and
operatively engaging said stirrup, said
member being slideable on the lever at right
angles to the stirrup, and means to adjust
said member.

24. In a top roll saddle mechanism, the
combination with a top roll saddle, of a
stirrup for applying weight thereto and pro-
vided with a laterally-extending finger, a

weighted lever having a slot to receive said finger which slot extends at right angles to the length of the stirrup, and means for adjusting said finger in said slot.

- 5 25. In a top roll saddle mechanism, the combination with a top roll saddle, of a stirrup for applying weight thereto and provided with a laterally-extending finger, and a weighted lever having a slot which extends at right angles to the length of the stirrup and in which said finger is received, said finger being adjustable longitudinally of the slot to vary the relative length of the lever arms of the lever.
- 10 15. 26. In a top roll saddle mechanism, the

combination with top rolls, of a top roll saddle resting thereon, a pivotally-mounted weighted lever provided with an opening, and a stirrup suspended from the saddle and having a laterally-extending finger entering said opening and constituting the fulcrum connection between the lever and stirrup.

In testimony whereof, I have signed my name to this specification, in the presence of 25 two subscribing witnesses.

LEWIS T. HOUGHTON.
